US0D1054253S

(12) **United States Design Patent** (10) Patent No.: **US D1,054,253 S**
(45) Date of Patent: **** Dec. 17, 2024**

(54) **DISPOSABLE BOWL**

(71) Applicant: **Arvum Beheer BV**, Ede (NL)

(72) Inventor: **Albert Jan van der Velde**, Ede (NL)

(**) Term: **15 Years**

(21) Appl. No.: **35/518,670**

(22) Filed: **Aug. 22, 2023**

(80) **Hague Agreement Data**

Int. Filing Date: **Aug. 22, 2023**

Int. Reg. No.: **DM/232068**

Int. Reg. Date: **Aug. 22, 2023**

Int. Reg. Pub. Date: **Oct. 13, 2023**

(51) **LOC (14) Cl.** 07-01

(52) **U.S. Cl.**

USPC **D7/566**

(58) **Field of Classification Search**

USPC D7/550.1, 554.2, 558, 566, 584;
D30/129

CPC A47G 19/00; A47G 19/30
